DESIGN FOR A BOX

Eugene Coleman, North Hollywood, Calif.

Application February 5, 1944, Serial No. 112,451

Term of patent 7 years

(Cl. D58—12)

To all whom it may concern:

Be it known that I, Eugene Coleman, a citizen of the United States, residing in the city of North Hollywood, county of Los Angeles, and State of California, have invented a new, original, and ornamental Design for a Box, of which the following is a specification, reference being had to the accompanying drawing, forming a part thereof.

Fig. 1 is a perspective view of a box showing my new design, and

Fig. 2 is a top plan view of the box.

The irregular broken lines on the front panel of the box represent a textured surface which is continuous throughout the whole surface of the several panels of the box, namely, the front, side, back and top panels.

I claim:

The ornamental design for a box, as shown and described.

EUGENE COLEMAN.
